UNITED STATES PATENT OFFICE

WILLIAM C. STEVENS AND GEORGE J. MEUER, OF MILWAUKEE, WISCONSIN, ASSIGNEES, BY MESNE ASSIGNMENTS, TO CUTLER-HAMMER INC., OF MILWAUKEE, WISCONSIN, A CORPORATION OF DELAWARE

VACUUM-TUBE SOCKET

Application filed December 8, 1924. Serial No. 754,489.

This invention relates to vacuum tube sockets.

An object of the invention is to provide a socket for panel board mounting, the parts of the socket being designed for assembly on and firm securement to the panel board, thereby obviating the necessity for prior assembly of the socket parts on the usual individual insulating base.

10 Other objects and advantages of the invention will hereinafter appear.

In the accompanying drawing, wherein are illustrated certain of the embodiments which the invention may assume in practice;

15 Fig. 1 is a top plan view of a panel board with two of the sockets mounted thereon;

Fig. 2 is a bottom plan view of Fig. 1;

Fig. 3 is a vertical sectional view taken on the broken line 3—3 of Fig. 2;

20 Fig. 4 is a vertical sectional view taken on line 4—4 of Fig. 2 showing a modified form of shell and securing means therefor, and

Fig. 5 is a partial sectional view showing another modified form of securing means.

25 Referring to the drawing, in which like parts are designated by like characters of reference in the several figures, the socket at the left will first be described.

The socket comprises a relatively thin cylinder or shell 5 of insulating material, such as 30 example, as that sold commercially under the name of bakelite, adapted to project through an aperture 6 in the panel board 7. Shell 5 is provided near the bottom thereof with a plurality of spaced openings 8. Contact clips 9 are adapted to project through the respective 35 openings 8, and are provided at opposite ends thereof with pairs of lugs or ears 10 and 11. Lugs 10 are adapted to be definitely positioned within shell 5 for cooperation with the 40 prongs or electrode terminals of a vacuum tube (not shown). Reinforcing members 12 are also adapted to project through said openings 8 and are adapted to be placed directly 45 below contact clips 9 to increase the rigidity of said contact clips. Said clips and reinforcing members are secured to panel board 7 by means of screws 13, which project through apertures 14 and 15 in panel board 50 7 and contact clips 9, respectively, and into

engagement with the screw threaded openings 16 in the reinforcing members 12.

As clearly shown in Fig. 3, clips 9 and reinforcing members 12 are adapted to project through the openings 8 in shell 5. The size of openings 8 closely approximates the combined cross-sectional areas of contact clips 9 and reinforcing members 12 to provide a snug fit therewith. Said arrangement together with the rigid clamping of said clips and said reinforcing members to panel board 7 by means of screws 13, provides for rigidly securing shell 5 and panel board 7 against relative movement.

55 The contact clips 9 are of the type shown and described in the copending application of George J. Meuer and William C. Stevens, Serial No. 737,516, filed September 13, 1924, and since no claim is made herein to the clips per se further description thereof is deemed 60 unnecessary.

The shell 5 is provided at the upper end thereof with a vertical notch 17 for cooperation with the usual pin or projection on a vacuum tube to insure engagement of the 75 prongs of the vacuum tube with the proper contact clips.

In assembling the device, a shell 5 is inserted into and through an aperture 6 in the panel board 7 so that the upper edges of 80 openings 8 are in line with the rear face of panel board 7. Clips 9 are inserted from the inside of shell 5, through openings 8 so that the apertures 15 are in register with apertures 14 in the panel board. Lugs 11 are preferably 85 upturned prior to insertion of the contact clips within the shell 5, and to accommodate the same the openings 8 are provided with pairs of spaced notches 8^a (as illustrated in Figs. 3 and 5). Reinforcing members 12 are 90 next inserted through openings 8 from the outside of shell 5, so that screw threaded openings 16 register with apertures 14 and 15 of panel board 7 and contact clips 9, respectively. As will be obvious, however, clips 9 and members 12 may be simultaneously inserted from the inside of shell 5. Screws 13 95 are next inserted into apertures 14 and 15 and screwed into screw threaded openings 16 of reinforcing members 12, thereby clamping 100

said clips and reinforcing members to panel board 7, and thereby securely fastening shell 5 to said panel board as aforesaid. Nuts 18 are threaded onto screws 13 to serve as lock-nuts, whereas the same may also be employed for temporary securement of lead wires to contact clips 9 when soldering is not resorted to.

Referring now to the socket illustrated at 10 the right-hand side of Figs. 1 and 2, and in Fig. 4, the same comprises a relatively thin cylinder or shell 19 of insulating material which is adapted to project into an aperture 6 in panel board 7 and to abut contacts similar to those aforesaid. Shell 19 is provided adjacent the outer face of the panel board with a plurality of spaced openings 20. Clamping members 21, preferably of insulating material and having reduced portions 22, 15 are adapted to be secured to the outer face of panel board 7 by means of screws 13 and the reduced portions 22 of clamping members 21 are adapted to penetrate shell 19 through said openings 20. As clearly shown at 24 in Fig. 25 the reduced portions 22 of clamping members 21 are adapted to engage or bite into the walls of openings 20 in shell 19 upon tightening of screws 13, thus serving to rigidly clamp the shell against the contacts at 30 the rear of the panel board.

The contact clips 9 of Fig. 4 are of the construction heretofore described and are adapted to be secured to the rear face of panel board 7 by means of screws 13. Lugs 35 10 of contact clips 9 are adapted to extend into shell 19 and to be definitely positioned therein for cooperation with the prongs or electrode terminals of a vacuum tube (not shown). Reinforcing members 23 engage a portion of clips 9 and are adapted to be clamped thereto by the screws 13 which pass through clamping members 21, the panel board 7 and clips 9, and thread into screw threaded openings 16 in said reinforcing members. Said reinforcing members are adapted to increase the rigidity of the contact clips and hence of the abutment for the shell 19, and, as will be apparent, the shell may be firmly clamped to the panel board by 45 50 tightening screws 13.

Shell 19 is also provided at the upper end thereof with a vertical notch 17 as aforesaid in connection with shell 5. Here it may be stated that, in use, a vacuum tube 55 is inserted into shell 5 or shell 19 with the usual lateral pin on said tube in alignment with notch 17, only a straight or vertical movement of the tube being necessary to effect contacting and holding of the prongs 60 of said tube by the contact clips 9; whereas the tube may be removed from the shell by a like vertical movement in the opposite direction.

In positioning and securing shell 19 with 65 respect to the panel board 7, said shell is in-

serted into aperture 6 so that the lower edge thereof is in alignment with the rear face of panel board 7. Openings 20 are so spaced from the lower edge of shell 19 that the same will register with the reduced portions 22 of 70 clamping members 21 when the latter are placed in position. Contact clips 9 are positioned on the rear face of panel board 7 directly below clamping members 21, said contact clips abutting the lower edge portion of 75 shell 19, the lugs or ears 10 of said contact clips extending into shell 19 and the apertures thereof registering with apertures 14 in the panel board. Reinforcing members 23 are then placed in position upon contact clips 80 9, the screw threaded openings 16 thereof registering with the apertures 15 in the contact clips. Screws 13 are inserted through clamping members 21, apertures 14 and 15 in the panel board 7 and the contact clips 9, 85 respectively, and are screwed into the screw threaded openings 16 in reinforcing members 23 to thereby secure said clamping members, contact clips, and reinforcing members to the panel board. The portion of shell 19 between openings 20 and the lower edge of the former will be clamped between the clamping members 21 and the upper face of contact clips 9.

Referring now to Fig. 5, the same illustrates a modification of the means for securing the shell and contact clips to the panel board. Rivets 25 are employed for securing said parts in assembled relation in lieu of the screws 13 employed in connection with 100 the aforesaid sockets. By means of rivets 25, the shell and contact clips are rigidly and permanently secured to the panel board and tampering with or loosening of the assembled parts is prevented.

What we claim as new and desire to secure by Letters Patent is:

1. In a vacuum tube socket for panel board mounting, the combination with a cylindrical shell to extend through the panel board and means to secure said shell to the panel board, said means including elements secured to the rear face of the panel board and detachably engaging said shell, said elements having integral contact clips extending into 115 said shell.

2. In a vacuum tube socket for panel board mounting, the combination with a perforated panel of insulating material, of a cylindrical shell of insulating material adapted to fit into said perforation, said shell having a plurality of circumferentially spaced perforations arranged in a common plane, and means to secure said shell and panel to each other, said means including a plurality of combined contact clips and wire terminal members freely insertable through said spaced perforations, said combined contact clips and wire terminal members being detachably secured to the rear face of said panel 125 130

and detachably engaging said shell for support of the latter.

3. In a vacuum tube socket for panel board mounting, the combination with a perforated panel of insulating material, of a cylindrical shell of insulating material adapted to fit into said perforation, said shell having circumferentially spaced openings, means for detachably securing said shell and panel to each other, said means comprising a plurality of combined contact and terminal members secured to the rear face of said panel, and elements associated with said members for engagement with the walls of said openings to hold said shell and panel against relative movement.

4. In a vacuum tube socket for panel board mounting, the combination with a perforated panel of insulating material, of an open-ended cylindrical shell of insulating material insertable within said perforation, said shell having circumferentially spaced openings substantially flush with one face of said panel, elements extending into said openings for engagement with the walls thereof, terminal members on the rear face of said panel, contact clips integral with said terminal members and adapted to be positioned within the lower end of said shell, and means for detachably securing said elements and said terminal members to the panel whereby said shell and said panel are held together.

In witness whereof, we have hereunto subscribed our names.

35 WILLIAM C. STEVENS.
GEORGE J. MEUER.
